CONTINUOUS AMALGAMATOR

Harry H. Culmer, Chicago, Ill., assignor of one-tenth to Mary Susanna Miller, Chicago, Ill.

Application June 1, 1936, Serial No. 82,875

1 Claim. (Cl. 209—190)

This invention relates to a new and improved method and apparatus for continuously amalgamating metals, and separating the amalgams from the free mercury.

5 The main objects of the present invention are to provide a method and apparatus for separating metals from their natural ores and other containing compounds by amalgamation; to provide an apparatus for continuously separating amalgams so formed from their entraining gangue compound, and simultaneously removing the amalgams as rapidly as formed from the mercury bath so that the excess mercury is immediately available to take up more amalgams with 10 out the intermediate necessity of retorting the whole of the mercury used; to provide an improved method and means for recovering free mercury in an amalgamation process; to provide a series of recovery steps in an amalgamation 15 process for recovering free mercury; to provide an improved apparatus for forcing ore into a mercury bath; to provide an apparatus wherein the mercury bath is subjected to an electrical field; and to provide an apparatus which is simple in construction and operation, and requiring a minimum amount of attention to operate.

20 While it is old in the art to create amalgams, it has been extremely difficult to effect sufficient contact of all metallic particles with the mercury, owing, in a great degree, to the fact that mercury in the presence of water forms a film over the surface of the mercury or between the water and the mercury. Also when the ores and other finely divided metals are passed in fine or 25 fairly coarse condition over this film, they do not have enough affinity for the mercury to break through the film and into molecular re-arrangement freely enough to give the mercury opportunity to take them up, and this results in a 30 decided drop in the efficiency of the known methods, and results in some of the metals passing from the amalgamating table plates and the like out into the tailings.

Especially is this true when the process of 35 combining the metals with the mercury is to be accomplished in and from a continuous stream of flowing water, as has been heretofore desirable, and the means in common practice.

I am aware of methods of batch treatment 40 where the mercury and divided metals and ores are shaken together in barrel mixers and mills that result in great loss of mercury by breaking it up into fine globules and losing it in the tailings. Finely divided mercury known in the art 45 as flour of mercury, requires laborious treatment

of the tailings to effect the recovery of such lost mercury; and in most cases this mercury is abandoned in the tailings of the mill, which is a costly practice.

An illustrative embodiment of my invention is 5 shown in the accompanying drawings, in which

Fig. 1 is a view of the amalgamating system with portions shown in section.

Fig. 2 is a cross sectional view of the amalgam 10 concentrator.

Fig. 3 is a cross sectional view of the amalgam filter press showing the piston at the upper portion of the cylinder.

Fig. 4 is a cross sectional view of the centrifugal amalgamating pump and attached mercury 15 bath.

Fig. 5 is a cross sectional view of the mercury bath taken on line 5—5 of Fig. 4.

Fig. 6 is a diagrammatic layout or flow sheet of 20 the wet amalgamating process.

Fig. 7 is a diagrammatic layout or flow sheet of the dry amalgamating process.

The apparatus containing my amalgamating system comprises a centrifugal pump 1 connected by shaft 2 to an electric motor 3, which is mounted on a base 4. A receiving hopper 5 communicates with the central intake of the pump 1, into which ore 6 is fed by means of a traveling belt 7 which is driven by a drum 8 through drive belt 9 by a driving means, not shown.

25 Pipes 10 provide the water supply for flushing the ore 6. A mercury bath 12 is located at the base of the pump 1, below the blades 11, and is provided with a partition 13 for dividing the bath into a front compartment 14, and a back compartment 15, as shown in Fig. 5.

30 Pipes 10 provide the water supply for flushing the ore 6. A mercury bath 12 is located at the base of the pump 1, below the blades 11, and is provided with a partition 13 for dividing the bath into a front compartment 14, and a back compartment 15, as shown in Fig. 5.

A mercury inlet pipe 17 is connected at one end to the side walls in front compartment 14 of the mercury bath 12, and one end of the outlet pipe 18 is connected to the side walls of the back compartment 15 of the mercury bath 12.

The other end of the mercury inlet pipe 17 is bent in the form of a coil 19 which is housed in a container 20 and is surrounded by solenoid 21 having lead wires 22—22 which are connected to a source of current, not shown. The other end of the outlet pipe 18 is connected to an amalgam washer 23, through a valve or stop cock 24. Three separating baffles 25, and three concentric baffles 26 are symmetrically housed within the washer 23. Water pipe 27 provides the wash water for the washer 23 and is provided with a valve 28. The washer 23 is also provided with an outlet pipe 29 through which the water is drained off. A force pump 30 is connected to 45

50 55

the bottom of the amalgam washer 23 by a pipe 31 having a valve 32.

The force pump 30 is connected to the amalgam concentrator 34 through pipe 33. The bottom cap 35 of the concentrator 34 is provided with an aperture into which a plug 36 having a central passageway 37 is threaded.

5 A stack of circular filter discs 39 is secured to the plug 36 and the discs 39 are provided with a central opening registering with the passageway 37. The discs 39 are held in place on the plug 36 by bolts 40, which are threaded through the solid cover plate 41. A cylinder 42 surrounds the stack of filter discs 39 and is held in place in the concentrator by the 10 sloping annular shelf and guide 43. Valve 44 and check valve 45 are connected to the return pipe 46 which is connected at one end to the passageway 37 and at the other end to the mercury inlet pipe 17. The concentrator 34 is also provided with an air pressure system, not shown. Air 15 under pressure is delivered through an air inlet pipe 47 with an attached air pressure indicator 48 into the concentrator 34. The air in the concentrator may be released through the outlet pipe 49 having a valve 50, in the event that the air pressure in the concentrator becomes too great. The bottom cap 35 of the concentrator 34 is also provided with an outlet 51 which is connected by pipe 52 through valve 53 and check 20 valve 54 to the upper end of the side wall of the amalgam filter press 55. The filter press 55 is provided with an upper piston 56 having a connecting rod 57 mounted therein which is driven by a drive mechanism, not shown, and which 25 connecting rod is seated, through a packing gland 58, in the filter head 59.

The filter head 59 is also provided with an adjustable cover plate 60 which holds the gland packing in place. The piston 55 is provided with 30 an integrally formed smaller or central piston 61, and the piston 61 is provided with a still smaller or lower piston 62. A passageway 63 extends downwardly through the pistons 56 and 61, and is provided with a ball check valve 64 at its lowermost end. The pistons 61 and 62 are slideable in the interconnected cylinders 65 and 66 respectively. Bolts 67 clamp the plate 68 against the bottom wall of the casing 69 and hold the stack of filter plates 70 in place. Each filter plate 70 is provided with circular apertures and when the plates are stacked and arranged in the position shown in the drawings, the apertures in each plate will be aligned and will form the passageways 71 which are arranged to communicate with the passageways 71'. By aligning the apertures 35 they will also provide a central passageway of the same diameter as the diameter of the walls of the cylinder 65. The outer end of the passageway 71' is internally threaded for the reception of a pipe 72 having a check valve 73 and a shut-off valve 74 mounted therein. The pipe 72 is also connected to the T 75 located on the outlet pipe 76 below the concentrator 34. The cylinder 66 which is formed in the bottom plate 68, lower filter press 40 head 76 and plug fitting 77, is provided with an outlet pipe 78. An adjustable pressure relief valve 79 is interposed between the outlet pipe 78 and the cylinder 66.

In operation my continuous amalgamating system 45 may be used with or without water in the initial mixing step.

The flow sheet disclosing the operation using water in the initial step is illustrated in Fig. 6 and the operation which does not use water is shown 50 in the flow sheet of Fig. 7, the principal difference

being in the milling of the ore and in the discharge of the lighter materials from the centrifugal pump exhaust outlet 80.

In operating the wet amalgamating process such as is illustrated in Fig. 6 and shown in detail in the drawings, wetted milled ore is fed into the receiving hopper and is carried into the central opening of the pump where the rapidly revolving blades of the centrifugal pump throw the stream of ore and water in a downward direction and into 10 a mercury bath. The direction of flow is illustrated by the arrows shown in Fig. 4 of the drawings.

The ore is thrown with sufficient force that it breaks through the film formed on the surface of the mercury so that all particles of precious metals are forcibly delivered into the mercury within the bath to form amalgams. The field set up by the solenoid located beneath or surrounding the mercury bath causes a more pronounced absorption of 15 the metals by the mercury. By heating the mercury the amalgamating action is accelerated and the electrical field produced by the solenoid at the same time breaks down the colloids which hamper amalgamation.

All of the ore leaving the blades of the centrifugal pump is forced or driven into the mercury bath and tends to drive the mercury in the direction of the rotation and motion of the blades in the front compartment of the bath, even 20 though the blades at no time contact the mercury in the bath itself. This causes a circulation of the mercury in the bath and produces a higher head of mercury in the outlet end of the bath.

The baffle plate in the mercury bath causes a 25 recirculation through the back compartment to complete a circuit of the mercury stream, and allows it to reenter the front compartment to repeat its action. The direction of motion is shown in Fig. 5.

The mercury is maintained in a compact stream by the novel and particular action caused by this construction that continuously breaks up the overlying film produced on the surface of the bath and at the same time causes all of the particles of metal carried by the incoming hydraulic stream to be thrown into forceful impingement with the mercury stream. By rapid recirculation of the hydraulic stream through control of the material leaving the pump, I am able to cause a rapid, repeated forceful impingement of all the metal contents upon and into the same stream of mercury whereby these particles of metal, no matter how finely divided, are forced by pressure into the mercury stream to very effectively form the desired amalgams.

The movement of the newly formed amalgams out of the zone of impingement caused by the circulation of the metal and mercury in the bath, causes a fresh, bright surface to be presented at all points of contact for the finely divided particles and to cause a free field of entry into the mercury stream or bath.

The amalgam formed in the mercury bath, together with the entrained free mercury, will flow 60 into the amalgam washer through the outlet pipe where it is washed with water which is constantly being circulated in the washer. The amalgam and entraining mercury will then be spread in the washer by the baffles contained therein so that the amalgam and mercury become thoroughly washed by the time they pass entirely through the washer. The free mercury and amalgam will eventually settle in the bottom of the washer and they are drawn from the washer by the action of the force 65 70 75 76

5 pump through the outlet pipe, and the mixture is delivered to the top of the concentrator. Any entrained dross that accompanies the amalgam and entrained mercury into the washer will be carried off by the stream of water through the water outlet.

10 The air pressure entering at the top of the concentrator acts as a piston forcing part of the free mercury against and through the stack 10 of filter discs and the mercury will accumulate in the central passageway whence it is returned to the mercury bath by suitable piping passing through the heated coil of the inlet pipe which is placed in the compartment with the solenoid. 15 The air pressure supplied to the concentrator will also force the amalgam along the sides of the filter and downwardly through the outlet pipe, whence it will be forced into the upper section of the amalgam filter press.

20 Figure 1 of the drawings shows the piston of the filter press at the lower end of its stroke, and Fig. 3 shows the piston at the upper end of its stroke. As shown in Fig. 1 with the piston at the lower end of its stroke, the upper part of 25 the cylinder will be filled with amalgam concentrate, with whatever free mercury that manages to escape from the concentrator. When the piston is raised, the amalgam concentrate and free mercury will flow through the 30 passageway located in the upper and central pistons, and out into the central cylinder. On the down stroke of the piston, the amalgam concentrate will be under great pressure and will be forced against the stack of filter plates where 35 substantially all of the free mercury remaining will be forced through the filter discs and returned by the piping arranged for that purpose to the mercury bath. The amalgam concentrate is forced to the bottom of the lower cylinder, and will be compressed by the lower piston 40 against an adjustable relief valve, and the amalgam emitted from this filter press is substantially a dry amalgam, containing very little if any free mercury. The product is a substantially solid mercury amalgam.

45 Practically all of the unamalgamatable materials and entrained dross are ejected by the mercury. By the action of the blades in the centrifugal pump, the ejected material is carried along by the water stream and ejected

5 through the exhaust outlet of the pump. A very small film of light dross material may be entrapped when the amalgam is withdrawn into the washer but this will be freed and carried off in the washing step.

10 The function of the amalgam washing is to remove any unamalgamated material which may be mixed with or entrained by the mercury withdrawn from the bath.

15 In the amalgam concentrator the product assumes a central stage in that it is still fluid enough to flow to the amalgam filter press where it is again subjected to such great pressure against the filters that it assumes a semi-solid state. In this semi-state, however, it is repeatedly stripped down from the plates by the pistons and packed as solid amalgam. The free mercury is removed through the filters as filtrate and returned directly to the mercury bath.

20 The pressure exerted by the downward stroke of the pistons has two actions, first to force all excess mercury through the filter, and second, to scrape down all solid and semi-solid concentrated amalgam that is formed on the filter 25 surface into the small cylinder, where it is compressed by the lower piston against the adjustable relief valve or plug, through which it is ejected as substantially dry amalgam.

30 This is of great utility because the product contains such a small percentage of mercury that the usual retorting capacity is reduced to a minimum, thereby saving fuel and the handling of excess weight of materials required by the well known methods.

35 It is to be understood that some of the details set forth may be altered or omitted without departing from the spirit of the invention as defined by the following claim.

40 I claim:

45 In the gold extracting art, the method of forming a mercury and gold amalgam, in a mercury bath divided to form a closed channel, which consists in projecting a stream of comminuted gold ore diagonally into the mercury, the direction of impact being inclined in only one direction with respect to the channel whereby circulation and consequent mixing of the mercury and ore are induced.

50 HARRY H. CULMER.
